NEW JERSEY

APPARATUS FOR CASING CURED LEAF TOBACCO

Application filed December 20, 1927. Serial No. 241,420.

This invention relates to an improved method of casing cured tobacco in accordance with the general practice set forth in Patents 1,585,476 and 1,585,477 dated May 18, 5 1926, and more particularly to a method for accelerating the casing operation.

That is to say, the present method has in view the carrying forward of the general type of apparatus and the method referred 10 to in the above patents, but aims to provide means whereby the casing operation will not only be accelerated but the capacity of the machines will be greatly increased. Accordingly, to that end the invention contemplates 15 a method wherein the leaf tobacco is subjected to a confined atmosphere of moving air laden with moisture to approximately the saturation point, the said air being circulated in and around the leaves of tobacco 20 in the suspended hands to effect even distribution of moisture to the inside leaves as well as to the outside leaves. In that connection the invention contemplates a gentle circulation or flow of the confined moisture laden atmosphere which will avoid the concentration 25 of moisture at any particular location within the apparatus thereby preventing over-casing of certain of the leaves and the starving of others.

With the above and other objects in view which will more readily appear as the nature 30 of the invention is better understood, the same consists in the novel construction, combination and arrangement of parts herein- 35 after more fully described, illustrated and claimed.

A preferred and practical form of apparatus for carrying the method into effect is illustrated in the accompanying drawings in 40 which

Figure 1 is a vertical longitudinal sectional view of the improved apparatus.

Figure 2 is an enlarged detail vertical sectional view of the construction shown in 45 Figure 1.

Figure 3 is a vertical transverse sectional view taken on the line 3—3 of Figure 2.

Similar reference characters designate corresponding parts throughout the several figures of the drawings.

In carrying the present invention into effect it is proposed to provide means for hastening or accelerating the casing operation by providing for a more effective and uniform distribution of moisture laden air than is possible where the tobacco merely hangs in such an atmosphere until it becomes properly cased. When a hand of tobacco is suspended in a moisture saturated atmosphere the outer leaves and the tips and edges of the under leaves absorb the required degree of moisture quickly with respect to the time required for the concealed or protected leaves at the core of the hand. Heretofore, due to the way that the tobacco must be suspended in the moisture laden atmosphere the casing process has been less speedy than desired. Accordingly, with a view to speeding up the casing operation under the same circumstances and conditions and for the same purposes as set forth 55 in the former patents referred to, it is proposed to gently move or circulate the confined moisture laden air in and about the leaves of tobacco, thereby not only reducing the time element of the casing operation but also increasing the capacity of the machine by reason of more quickly releasing successive 60 batches of tobacco.

In the foregoing connection it is pointed out that the action of circulating the moisture laden air according to the present method is to be distinguished from forcing or blowing such air under pressure since it only is intended to gently move or circulate the moisture laden air so that it will thoroughly and adequately reach, in a minimum period, all of the absorbing surfaces of the tobacco leaves. In that connection, it is pointed out that the forcing or blowing of the moisture laden air in a stream would localize the air jets in spots thereby spotting the leaves and therefore cause precisely the undesirable result which this series of inventions are intended effectually to obviate by providing adequate means for distribution and circulation.

When the air is not circulated, and the tobacco is merely allowed to absorb moisture from the confined air, it has been found that while the casing is very effective nevertheless it requires a relatively extended period of 100

time which limits the capacity of the machine. When the tobacco is hung in the apparatus the leaves are dry and loosely separated, but the outside leaves (or, when the hand is placed 5 astride a partition having a wick, the inside leaves) take on the moisture quickly because they are directly exposed and thus become limp and fall together or have a tendency to pack and form a "blanket" which prevents 10 the moisture laden air from reaching the interior leaves of the hand unless and until adequate time is allowed for the inside leaves to have their avidity for moisture satisfied.

Accordingly, the present invention aims to 15 circulate the moisture laden air gently through the leaves of the hands of tobacco in such a way that while the leaves are comparatively stiff and separated, the moisture laden air will be circulated through and about all 20 of them and thus speed up the casing of the interior leaves to more closely approximate the normal casing period of the outer leaves and thus on the whole, greatly accelerate the 25 entire casing process.

Therefore, it is pointed out that the present 30 process contemplates the gentle moving or shifting of the confined moisture laden air in such a way that it is brought to all of the surfaces of the leaves of the hands of tobacco uniformly and within a comparatively short 35 space of time.

According to the type of apparatus shown 40 in the drawings, it is proposed to provide a receptacle designated generally as 1 and provided with a tight fitting cover 2, the same having therein an upper reservoir 3 and a lower reservoir 4 which communicates with the upper reservoir by means of a pipe line 5 having therein a pump 6 which maintains 45 the proper level of water in both reservoirs, with the aid of the ball float valve device V in the upper reservoir 3 which controls the water from the feed pipe or source of supply S.

46 Suspended from the upper reservoir or well 3, entirely around the inside of the machine, are suitable wicks 7 of burlap or the like which extend from the upper reservoir downwardly into the bottom reservoir thereby to 50 provide a moisture saturated interior wall which surrounds a foraminous basket designated generally as B and having the vertical screened wall portion 8 lying adjacent the wicks to prevent the contact of the tobacco therewith. The bottom wall of said basket B 55 is separate from the side walls and is constituted by a screen member 9 which is horizontally disposed and overlies the reservoir 4, and is supported upon the ribs or brackets 60 10 on the inside wall of the receptacle and has the upper side thereof between the vertical walls 8 covered with a sheet of burlap 11. The bottom wall 9 of the basket therefore 65 forms the support on which the vertical walls of the basket are mounted.

Also the bottom wall 9 of the basket B is provided with a plurality of openings, at which suitable partitions or racks designated generally as R are provided for the purpose of supporting the hands of tobacco. As will be observed from the drawings, the racks are alternately of different height, that is certain of the racks are of greater height than the racks on either side thereof, thereby to permit of placing the hands of tobacco on the 70 rack in substantially vertical staggered relation so that they will be more readily exposed and more freely absorb the required amount of moisture. Each of the racks R includes a horizontal or transverse water trough 12 75 having therein a wick 13 which is looped into the trough so that the opposite sides thereof fall downwardly to the base of the basket and may drip or drain into the lower reservoir 4. At each side of the racks 13 are arranged foraminous guard walls or 80 screens 14 which extend the full length of the wick and have the upper ends thereof provided with the inturned guard plates 15 which are perforated as at 16 to permit of 85 the air making its way into the part of the hands of tobacco which are tied tight together.

For the purpose of supplying the troughs 12 with water from the upper reservoir 3, 90 there is provided a pair of supply pipes 17 which are swiveled as at 18 to the reservoirs and have the depending feed pipes 19 and 20, the former supplying the troughs of the lower racks and the latter supplying the 95 troughs of the high racks. Thus, the troughs are supplied from the pipe manifolds 17, which, for convenience, may be pivoted or swiveled to the sides of the apparatus so that they may be lifted vertically when desired. 100

From the foregoing it will be apparent that the racks R as well as the entire basket are equipped with wicks which are continuously supplied with water to thereby maintain a uniformly saturated atmosphere throughout 110 the closed receptacle. By reason of the provision of guard plates 15 at the top of the racks, the hands of tobacco are protected from direct contact with the water while at the same time, the moistened wick is brought 115 well up into the center of the tied ends.

Referring now more particularly to the means for carrying into effect the novel and distinctive feature of the present invention, it will be observed that each of the racks R 120 has associated therewith, air circulating means which communicates with a trunk line wherein the air is circulated over the water in the lower reservoir and thus picks up the moisture from the bottom of the reservoir 125 and insures its distribution directly at and to the hands of tobacco suspended by, or supported on, the racks R.

As shown in Figs. 1 and 2 the air circulating system comprises a conduit, manifold 130

or trunk line 22 which extends throughout the length of the receptacle and is of transversely arched shaped formation, being supported on the bottom of the receptacle by the feet 23. This arrangement permits water in the reservoir 4 to provide a passage which is water-sealed at the bottom so that air impelled through the passage and over the water will become saturated with moisture as it is gently fed into the offset distributing pipes which are connected with the top of the manifold 22.

The distributing pipes are designated generally as D and are preferably of substantially T-shaped formation as will be clearly observed from Fig. 3 of the drawings wherein the upright portion 24 is connected at its lower end as at 25 with the metallic member which constitutes the conduit 22. The side walls of the pipe 24 are provided with a plurality of openings 24^a and the upper end thereof is provided with a horizontal connection 26 which in turn is provided with a plurality of laterally offset distributing nozzles 27 each provided with radially disposed ports 28 in addition to being open at the ends 29 thereby to distribute the air in all directions, and particularly direct it inwardly behind the screens 14 of the racks and against the wicks 13 so that the moisture laden atmosphere will be carried into the crotch of the hand through the perforations 16 in the guard plate 15 as well as through the slot or opening provided between convergently related guards 15 of the opposite screens 14.

For the purpose of maintaining a low head of pressure in the circulating system the conduit or manifold 22 is provided at one end with suitable air impelling means 30 which may be a fan or the like arranged within the casing and driven by a motor 31 supported on the outside of the receptacle. The impeller 30 is provided with an intake port 32 which communicates with the interior of the basket C and is also provided with a discharge conduit 33 which communicates directly with the water sealed passage which is provided by the arched conduit 22.

It will thus be apparent that when the looseleaved hands of dry tobacco are suspended on the racks R and the apparatus is ready to function, the humidified air confined within the receptacle will be gently circulated and distributed throughout the entire receptacle to evenly and uniformly distribute the moisture to all portions of the hands of tobacco so that the casing process will be greatly facilitated by the even distribution of the moisture, as previously indicated.

As will be observed from Fig. 2, the motor 31 which actuates the impeller 30 may be provided with a suitable connection 31^a for operating the water pump 6. Also as previously indicated, it is intended to supply the upper chamber or reservoir 3 with water which

rapidly makes its way into the lower reservoir 4 through the medium of the wicks 7 as well as the wicks 13 in the racks, water being supplied to the latter through the medium of the troughs 12 which are supplied by the piping system 17, 18, 19 and 20. Therefore, it is necessary to prevent the water in the lower compartment 4 from reaching such a level that the circulating system would not function or that the ends of the hands of tobacco would become immersed in water. The provision of the pump 6 however takes care of maintaining a proper supply of water in the lower reservoir while the float valve V maintains the proper liquid level in the upper reservoir 3 to replace the water which is absorbed by the tobacco during the casing process.

While it is not contemplated by the present invention to supply a heated atmosphere or heated vapor to the hands of tobacco, a heated atmosphere being particularly undesirable for casing purposes, nevertheless, since this type of apparatus is intended to be used in connection with ordinary city water supply systems, there are times when the water is very cold, and under these circumstances, it is desirable to bring the water within the receptacle to a normal temperature, that is approximately seventy to eighty degrees. To provide for this contingency, suitable electrical heating means 34 may be employed in the lower reservoir or tank 4 as shown in Figs. 1 and 2. This heater 34 may be of the conventional cylindrical type having suitable resistance therein and may be rendered operative by connecting the same with a source of current through the conventional detachable plug 35.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

We claim:

1. An apparatus for casing cured leaf tobacco including a closed receptacle, foraminous racks for supporting the hands of tobacco arranged within the receptacle, a water reservoir in the bottom of the receptacle, a member forming a manifold trunk line located at the bottom of the receptacle and underlying the said racks, said member cooperating with the water level in the reservoir to provide a passage whose bottom is formed by said water, a plurality of vertically disposed air distributing members arranged at the location of the racks and communicating with said conduit, and impelling means associated with said conduit.
2. An apparatus for casing cured leaf to-

5 tobacco comprising a closed receptacle, a plurality of foraminous racks of different height arranged within the receptacle, a water reservoir in the receptacle, a conduit forming member constituting a manifold trunk line and cooperating with the water in the reservoir to provide a water sealed passage, a plurality of circulating and distributing members communicating with the conduit member, and means for impelling air through said conduit and feeding the same to said distributing members adjacent the racks.

10 3. An apparatus for casing cured leaf tobacco including a receptacle, a cover for the receptacle thereby to provide a confined atmosphere within the same, means for suspending hands of tobacco within the receptacle, means for charging the air confined within the receptacle with moisture comprising upper and lower water reservoirs, means for maintaining the proper level of water in said reservoirs, and means for circulating the moisture laden atmosphere in and about the hands of tobacco comprising a conduit constituting a manifold, distributing passages communicating with the conduit and arranged at the location of the means for supporting the tobacco for distributing the moisture laden atmosphere in and about the leaves of tobacco, and impelling means communicating with said conduit and also with the receptacle for circulating and recirculating the confined moisture laden atmosphere.

15 4. An apparatus for casing cured leaf tobacco comprising a closed receptacle, a top water reservoir, a foraminous basket including a bottom member consisting of screen and burlap supported on the sides of the receptacle and a rectangular vertical side wall member formed of screen, a plurality of vertically disposed racks carried by the bottom wall of the basket member and each including opposite foraminous wall members having convergently related perforated guard plates at their upper ends, a water trough lying beneath said perforated guard plates, wick members arranged in said troughs and hanging downwardly behind the screen walls of the rack, a conduit forming member underlying the racks and having the bottom wall thereof formed by the level of the water in the lower reservoir, a plurality of substantially T-shaped air distributing heads communicating with the conduit and having side air circulating openings and also provided with perforated nozzles adapted to direct the air inwardly through the screens of the racks to a point beneath the guard plates, and means for impelling the air drawn from the basket through the conduit and to the air distributing members.

20 5. In tobacco treating apparatus, a liquid trough, means for supporting different portions of a hand of tobacco in spaced relation above and at opposite sides of said trough,

25 respectively, said supporting means being perforated, and means for directing a current of air across said trough and through the perforations of said tobacco supporting means.

30 6. In tobacco treating apparatus, a liquid trough, and a pair of perforated tobacco supporting members in the form of plates extending from opposite sides of said trough in upwardly convergent relation above the trough.

35 7. In tobacco treating apparatus, a liquid trough, and a pair of perforated tobacco supporting members in the form of plates extending from opposite sides of said trough in upwardly convergent relation above the trough, said plates terminating in spaced relation at their upper ends.

40 8. In tobacco treating apparatus, a liquid trough, a screen at the side of said trough, a wick adjacent to said screen, a perforated tobacco supporting member extending from said screen across at least a portion of the top of said trough, and means for directing a current of air through said wick and screen across the top of said trough and through the perforations of said tobacco supporting member.

45 9. In tobacco treating apparatus, a casing, a pair of spaced screens within said casing, a liquid trough between said screens, a wick hanging from said trough adjacent to the inner face of each screen, a pair of tobacco supporting members extending in upwardly convergent relation from said screens, respectively, above said trough, and means at the outside of each screen for directing a current of air through each screen and wick towards and across the top of said trough.

50 10. Means for casing cured leaf tobacco including a closed receptacle, moist air distributing units, means for supporting the hands of tobacco over the said units in a position permitting the moist air being directed inside of the hands toward the tied ends thereof, means for producing a moisture laden atmosphere within the receptacle, and a blower system for forcibly circulating the moisture laden air through said moist air distributing units.

55 In testimony whereof we hereunto affix our signatures.

RAMON FEBLES.
